UNITED STATES PATENT OFFICE.

JOSEPH SIEGEL, OF DETROIT, MICHIGAN, ASSIGNOR TO AMERICAN LADY CORSET COMPANY, OF DETROIT, MICHIGAN, A CORPORATION OF MICHIGAN.

CORSET.

Application filed May 28, 1923. Serial No. 642,038.

This invention relates to corsets and it is the object of the invention to provide a freely flexible corset comprising portions so shaped and connected as to give the garment a form adapting it to snugly conform to the body and more especially the hips of the wearer.

The invention consists further in the provision for attaching garment supporters to the corset.

In the drawings:—

Figure 1 is an exterior view of the improved corset, opened out;

Figure 2 is an interior view of the same;

Figure 3 is a front view of the garment in use;

Figure 4 is a side view of the same.

In these views, the reference character A designates a central strip, preferably elastic, which extends the full height of the garment at the rear thereof. To each lateral margin of said strip there are secured an upper hip section B and a lower back section C, said sections overlapping and being secured to the margins of the elastic strip and further being secured to each other in an overlapping relation. Clasp sections D, carried by the free ends of the hip sections B, marginally carry the coacting clasps or fasteners E. Flexible reinforcements F of steel or other suitable material are extended substantially the full length of the strip A between its margins overlapping edge portions of the sections B and C, and the rows

35 of stitching G which hold said reinforcements in place also attach the sections B and C to the strip A. In use, the sections B embrace the hips of the wearer, inclining downwardly toward each other at the front 40 of the body, as best seen in Figure 3. At the angles formed by the lower and front edges of said sections, hose supporters H are attached. The sections D, when the garment is in use meet at the front of the body, their 45 upper edges extending substantially along the waist line. To give a certain fullness to the rear and side portions of the sections B plaits J are laterally extended upon said portions from the rear ends of said sections, 50 said plaits being secured at the inner margins of the sections B by the stitching G but being free for the major portion of their extent. Said plaits adapt the sections B to snugly conform to the hip curvature. The 55 rear sections C have a lesser lateral extent

than the upper sections B, covering only the rear portions of the body. Hose supporters K are attached to the sections C preferably upon the downward extensions formed by the intersection of their outer and lower edges. The sections B have wide hems L formed along the lower margins, said hems being stitched to the sections C only along their upper edges and thus freely overlapping said sections C, and similar hems M upon the front upper edges of the sections B freely overlap the sections D.

The described garment is of such a form as to snugly embrace and confine the hip portion of the body, at the same time providing depending angular attachment portions for the hose supporters that will utilize the downward stress exerted through said supporters to eliminate slack and present a smooth un wrinkled surface to the outer garments. The plaited construction of the sections B secures the necessary fullness at the hips. The freely depending hems L add to the appearance of the garment as well as reinforcing the same. The garment derives a certain circumferential expandability throughout its entire height by the employment of elastic material to form the central rear strip A.

The several sections forming each of the similar halves of the garment are so shaped as to very snugly adapt themselves to the configuration of the lower portion of the body.

What I claim as my invention is:—

1. A corset comprising a back piece, and a pair of sections secured to opposite lateral margins of said back piece, and adapted to extend circumferentially to the hips of the wearer, and to extend downward toward each other at the front of the garment, the front edges of said sections forming substantially right angles with the top edges thereof, fastener sections secured to the front portions of each of said hip engaging sections, and projecting substantially in the direction of the bisector of said angle, and clasp members secured to each of said fastener sections.

2. A corset comprising a central strip at the back of the garment, and upper and lower sections secured to each lateral margin of said strip, members attached to said upper sections adjacent the upper outer corners thereof extending upwardly and outwardly, and having fastening means along

their outer edges, said members being adapted to meet at the front of the body of the wearer, with their upper edges substantially parallel to the waistline thereof, said upper sections being adapted to extend around the hips and downwardly from the waistline in the front, said lower sections being adapted to extend downwardly around the hips and terminate adjacent the sides of the body of 10 the wearer.

3. A corset comprising a central strip and a pair of sections secured to opposite lateral margins of said strip and adapted to extend circumferentially of the hips of the wearer, 15 and to extend downward toward each other at the front of the garment, the top edge of one of said sections and the front edge of the opposite section forming a substantially straight line, and hose supporters attached

to said sections at the point of intersection 20 of their front and lower edges.

4. A corset comprising a central strip at the back, and a pair of sections secured to opposite lateral margins of said back piece, members attached to said sections adjacent 25 the upper outer corners thereof and extending upwardly and outwardly therefrom, and having their upper edges substantially parallel to the waistline of the body of the wearer, said sections adapted to extend circumferentially of the hips of the wearer and to extend downward toward each other at the front of the garment, the intersection of the upper and front edges of said sections being secured to said members adjacent the 30 lower edges thereof.

In testimony whereof I affix my signature.
JOSEPH SIEGEL
